UNITED STATES PATENT OFFICE

ANDREW HILLIARD ATTERIDGE, OF LONDON, ENGLAND.

SUBMARINE BOAT OR OTHER VESSEL.

969,128.

Specification of Letters Patent. Patented Aug. 30, 1910.

Application filed September 11, 1906. Serial No. 334,145.

To all whom it may concern:

Be it known that I, ANDREW HILLIARD ATTERIDGE, a subject of the King of Great Britain and Ireland, residing at 26 Bath road, Bedford Park, London, England, have invented new and useful Improvements Specially Though Not Exclusively Applicable to Submarine Boats or other Vessels, of which the following is a specification.

10 My invention relates to improvements specially, though not exclusively, applicable to submarine boats or other vessels and the invention has especial reference to ballast tanks for submarine boats by means of which 15 ready adjustment can be obtained and this part of my improvement is specially, though not exclusively, applicable to submarine boats of the "no reserved buoyancy" type.

Another part of my invention relates to 20 improvements in apparatus for ventilating submarine boats and for releasing air from the ballast tanks; and by its means the air in the boats may be maintained pure when they are running awash.

25 I have illustrated types of my invention in the accompanying drawings, wherein; Figure I is a vertical sectional view of a portion of the ballast tank with my improvements mounted thereon. Fig. II is an elevation of the upper end of the main pipe and flare of the ventilating apparatus. Fig. III is an elevation and part section of the main pipe and its attached parts. Figs. IV and V are detail views, hereinafter referred to.

30 When the submarine boat is immersed so that the surface of the sea is flush with a given datum line on the conning tower, the main tank should be quite full, so that the water therein shall form a solid block, so to 35 speak, and have no free or movable water surface. The precise amount of water to so fill the main tank, and at the same time to keep the boat immersed to the proper depth, will vary under certain conditions. It is

40 therefore desirable to provide a ready means of adjustment so that the main tank shall contain the required amount of water without allowing this to have any free or rolling surface. To effect this and so carry my invention into effect, I affix to the top of the 45 ballast tank a cylinder or box 1 extending downward into the tank 2, the said cylinder or box being open at the bottom 3 so that there may be free communication between 50 the inside of the cylinder, under the piston hereinafter mentioned, and the ballast tank

and the top of the cylinder or box having an opening communicating with the external air. Within the said cylinder 1 a piston 4 is fitted attached to the bottom 5 of a threaded shaft 6 passing through a fixed threaded bearing 7 and having at its upper end a hand wheel 8, or polygonal extremity, or other device, for the turning of the said shaft. When this piston is moved downward, by 60 the turning of the said shaft, it presses the water beneath it from the cylinder into the ballast tank; and by moving this piston sufficiently far down it may completely fill the ballast tank and prevent any free surface 65 of water obtaining.

70 9 is a gland of any convenient kind. The dotted lines show the piston in its highest position, that is to say at the top of the cylinder.

If desired a relief valve for the release 75 of air might be fitted to the cylinder or to the ballast tank at any convenient point. In order to admit the requisite amount of water without leaving any free surface 80 thereof, water is admitted to the tank until the boat is sunk to the datum line. The water cocks are then closed and the piston is screwed down tight, care being taken of course if there be an air release valve in 85 the ballast tank, to close this after any air has been removed. The presence of some air beneath the piston and within the cylinder is not of importance.

From the upper cover 10 of the ballast 90 tank 2, I take a pipe 11, hereinafter termed the main pipe, extending upward through the roof 12 of the submarine boat and bend it over so that its end 13 points downward. Upon this end I place a flare 14 having a 95 perforated plate 15 (see Fig. IV) at its opening. This perforated plate not only has a number of perforations 16 for the admission of air, but it has also, at its center, a larger opening 17, surrounded by an annular flange 18 which acts as a seating for a light hollow metal ball 19. Above this and where the flare joins the end of the main pipe, is another plate 20 (see Fig. III) having a central orifice 21 with a similar flange 22, which also acts as a seating for the ball 19 when the latter is pressed upward by the action of a wave as hereinafter mentioned. That part of the main pipe which is between 100 the top 1 of the ballast tank and the roof 12 of the submarine boat is provided with two stop cocks 23, 24, preferably placed one 105 110

23 immediately over the ballast tank and the other 24 immediately under the roof of the boat. At an intermediate point between the two stop cocks is a small branch pipe 25 opening upward and capable of being closed in any convenient manner as for example by the stopper 26. In Fig. III I show two branch pipes 25 but the number may be varied as may be desired.

10 The action is as follows:—Let us assume that the submarine boat is running awash, and that the ball is in its normal position that is to say resting in the lower seating 18. The air will pass through the small perforations 16 in the lower plate, and will pass around the ball through the seating 22 in the upper plate, over the bend, downward through the main pipe, and into the interior of the submarine boat through the branch 20 pipe 25 which is normally open. Suppose now that a wave rises over the outlet of the main pipe. In doing so it will raise the ball 19 against the upper seating 22 and thus close the entrance to the main pipe. Assume however that the action is not sufficiently rapid and that some water passes the ball. This will do no harm unless sufficient enters to rise above the bend of the 25 pipe. Even then, however, no harm will be done as this water will simply run down the pipe 11, past the entrance of the upwardly extending branch pipe 25, and into the ballast tank, where it can be dealt with in the usual manner.

35 In the above description it has been assumed that the upper stop cock 24 is open. When it is desired to dive, the stop cock 24 is closed so that any admission of water is prevented. When the ballast tank is being 40 filled, the lower stop cock 23 is open and the pipe 11 then serves as an air release device for the ballast tank, any air in the tank escaping into the interior of the boat through the branch pipe 25 if the boat is submerged, or out through the flare if the boat is at the 45 surface. When the pump is started for bringing the boat to the surface, the lower cock 23 is opened, so that the air from the interior of the boat may pass through the 50 branch pipe down into the upper part of the ballast tank. When the natural ventilation through my apparatus is insufficient, a rotary fan or the like operated by an electro-motor may be attached to the branch pipe 25, either for the purpose of drawing in fresh 55 air or for the purpose of driving out impure air.

60 Of the apparatus which I have just described that part which relates to a bent pipe and ball valve is not broadly novel. Thus bent pipes similar to that shown in Fig. II fitted with flares such as 14 and containing ball or other gravity valves for the 65 purpose specified are well known. So far as this part of my apparatus is concerned

the novelty lies merely in surrounding the opening 17 by an annular flange 18 and a plate 15 containing perforations as 16. I believe, however, that it is novel to connect such pipe as 11 with the ballast tank for the purpose specified and to provide that pipe with the parts illustrated between the upper part of the ballast tank and the roof 12 of the boat.

Having thus described my invention, what 75 I claim as new and desire to secure by Letters Patent is:—

1. A ballast tank closed at the top and containing within it a cylinder or box fitted with a piston, the bottom of the said cylinder or box having an opening by means of which there is free communication with the interior of the ballast tank, and the top of the cylinder or box having an opening communicating with the external air, substantially as described and illustrated.

2. In a submarine boat, the combination of a ballast tank, a pipe leading from the interior of said ballast tank to the exterior of the upper part of the boat, the said pipe being provided with one or more valved branch-pipes located within the interior of the boat and adapted to place such interior in communication with the pipe for ventilation, and a hand-valve located within said pipe in the interior of the boat.

3. In a submarine boat, a ventilating pipe extending from the interior of the ballast tank to the exterior of the boat the said pipe being provided at its upper end with means 100 for permitting the inward passage of air but not of water and also fitted at an intermediate part with means for releasing air from the ballast tank into the interior of the boat substantially as set forth.

4. In a submarine boat, the combination of a ballast tank, a ventilating pipe leading therefrom to the exterior of the boat and provided with means for permitting the inward passage of air but not of water, two 110 independent hand valves for controlling said ventilating pipe, an air vent in said ventilating pipe at a point between the two said valves, whereby said interior air vent may at will be connected with the exterior 115 air or the air in the ballast tank or both.

5. In ventilating apparatus for submarine boats, the combination of a ventilating pipe extending to the exterior of the boat and having its outer end provided with a perforated plate having a valve-seat upon its inner side, a second valve-seat within the end of the pipe, a ball-valve co-operating with both said valve-seats and acting to completely shut off communication when resting upon the inner seat but permitting communication through said perforations when resting on the outer seat.

6. In a submarine boat, the combination of a ballast tank closed at its top for confin-

- ing the water therein, a compartment in the upper part of said ballast tank provided with a piston and the bottom of said compartment communicating directly with the 5 interior of said tank, means for operating said piston when the proper amount of water required for ballast is in the tank so as to force the water from the compartment into the tank in order to entirely fill the latter.
- 10 7. In a submarine boat, the combination of a ballast tank closed at its top for confining the water therein, a compartment in the upper part of said ballast tank provided with a piston and the bottom of said compartment 15 communicating directly with the
- interior of said tank, means for operating said piston when the proper amount of water required for ballast is in the tank so as to force the water from the compartment into the tank in order to entirely fill the latter, 20 the said compartment having considerably less cross sectional area than the tank.

In witness whereof I have signed my name to this specification in the presence of two subscribing witnesses.

ANDREW HILLIARD ATTERIDGE.
